Inventor:

Rufel Frisbie

UNITED STATES PATENT OFFICE.

RUSSEL FRISBIE, OF MIDDLETON, CONNECTICUT.

NUTCRACKER.

Specification of Letters Patent No. 24,018, dated May 17, 1859.

To all whom it may concern:

Be it known that I, RUSSEL FRISBIE, of Middletown, in the county of Middlesex, in the State of Connecticut, have invented 5 a new and Improved Machine for Cracking Nuts; and I do hereby declare that the following is a full and exact description thereof, reference being had to the accompanying drawings, and to the letters of reference marked thereon, which form a part 10 of this specification.

To enable others skilled in the art to make and use my invention, I will proceed to describe its construction and operation. 15 Figure 1 is a plan or top view. Fig. 2 is a sectional side elevation, showing the cam lever, joints, jaws, &c.; the dotted lines show the several parts in their position ready to receive the nuts to be cracked. 20 Fig. 3 is a side elevation of my invention, showing all the parts complete.

I make my invention of any suitable material, having the base of suitable form, as

at Figs. 1, 2, and 3, upon which I place a stationary jaw *b*, Figs. 2, and 3, and bearings for joints *c* and *a*, Figs. 2 and 3, of the cam lever *e* and movable jaw *f*, Figs. 1, 2 and 3. In the bearings *c*, Figs. 2 and 3, I place the journals of my cam lever *e*, the cam part of which works in a place made to receive it in the movable jaw. By elevating the cam lever *e*, as shown by the dotted lines in Fig. 2, the jaws *b* and *f* will be opened to receive the nuts; then by depressing the cam lever the jaws will be made to compress and crack the nuts.

What I claim and desire to secure by Letters Patent is—

The nutcracker substantially as described as a new and improved article of manufacture.

RUSSEL FRISBIE.

In presence of—

MARIA W. BARNES,
JONATHAN BARNES.
